United States Patent Office

Des. 200,924
Patented Apr. 20, 1965

200,924

FOOD VENDING UNIT

Otto E. Werner, Skokie, Ill., assignor to Automatic Canteen Company of America, Chicago, Ill., a corporation of Delaware

Filed June 18, 1962, Ser. No. 70,591

Term of patent 14 years

(Cl. D52—3)

FIG. 1

FIG. 2

FIGURE 1 is a perspective view of a food vending unit embodying my new design, and

FIGURE 2 is a plan view thereof.

The essential features of the design reside in the portions shown in full lines.

The rear of the food vending unit is substantially plain in appearance.

I claim:

The ornamental design for food vending unit, as shown and described.
